Primary Examiner — Cathron Brooks*Assistant Examiner* — Melanie Levy(74) *Attorney, Agent, or Firm* — Dicke, Billig & Czaja PLLC**(57) CLAIM**

We claim the ornamental design for an identification insert for recipient identification wrist band, as shown and described herein.

DESCRIPTION

FIG. 1 is an isometric view of an identification insert for recipient identification wrist band in accordance with the present disclosure;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.
